(57) **CLAIM**

(21) Appl. No.: **29/265,996**

The ornamental design for an endpoint for a videoconference, as shown and described.

(22) Filed: **Sep. 11, 2006**

DESCRIPTION

(30) **Foreign Application Priority Data**

Apr. 28, 2006 (NO) 20060217

FIG. 1 is a front perspective view of the endpoint for a videoconference embodying our new design.

(51) **LOC (8) Cl.** **14-03**

FIG. 2 is a back perspective view of the endpoint for a videoconference.

(52) **U.S. Cl.** **D14/130; D14/142; D14/159**

FIG. 3 is another front perspective view of the endpoint for a videoconference.

(58) **Field of Classification Search** D14/130,
D14/148, 146, 158, 155, 142, 496, 125, 126,
D14/240, 243; 348/14.01–14.16, 211.99;
370/352, 356; 382/557; 455/557, 566; 379/88.17,
379/90.01, 93.17, 93.19, 93.22, 102.06, 419,
379/420.01–420.04, 428.01–428.04, 433.01–436,
379/440, 441, 454, 900

FIG. 4 is a front view of a lower portion of the endpoint for a videoconference.

See application file for complete search history.

FIG. 5 is a right side perspective view of the endpoint for a videoconference.

(56) **References Cited**

FIG. 6 is a left side perspective view of the endpoint for a videoconference.

U.S. PATENT DOCUMENTS

FIG. 7 is a top perspective view of the endpoint for a videoconference.
